UNITED STATES PATENT OFFICE.

ARTHUR S. McNALLY, OF NEWARK, NEW JERSEY.

COLLAPSIBLE COIN RECEPACLE AND STAND.

Application filed September 16, 1921. Serial No. 501,092.

To all whom it may concern:

Be it known that I, ARTHUR S. McNALLY, a citizen of the United States, residing in the city of Newark, county of Essex, State 5 of New Jersey, have invented certain new and useful Improvements in Collapsible Coin Receptacles and Stands, of which the following is a specification.

This invention relates to receptacles for 10 coins suitable for desk stands and similar purposes, and relates more particularly to a receptacle having a front of cardboard or other stiff material, and having a back consisting of an envelope or similar receptacle, the front and back being arranged so as to 15 form a stable stand, and to permit coins to be inserted in a slot in the front and drop into the rear receptacle. When the receptacle is full, or when it is desired to transfer 20 the coins to a bank for deposit, or to any other place, the receptacle can be easily detached from the front.

A particular embodiment of my invention is shown in the accompanying drawings, in which Figure 1, is a perspective view of the collapsible coin receptacle and stand.

Figure 2 is a section of the receptacle and stand taken on the line 2—2 of Figure 1.

Figure 3 shows a modified form of my receptacle and stand in perspective.

Figure 4 is a section of the upper part of the modified form of receptacle and stand taken on the line 4—4 of Figure 3.

Figure 5 is a section of the upper part of the receptacle with the flap F' turned over the slot.

In the drawings, the front A, of cardboard or other stiff material, may be plain 40 or may have on it an ornamental design, a calendar, or other printed matter, and the name of a bank or other institution or company, or individual, and in its upper part it has a slot C, for the reception of coins D, or currency. The back B, is a receptacle, such as an envelope, of paper or similar material, thinner than that of the front, but stiff enough to form a support for the front and make a stable stand. The receptacle has two 45 parts, b and b¹, which are fastened together, in the usual manner of an envelope, to form a receptacle. At the upper end of the part b, adjoining the front A, is a slot C¹, which corresponds exactly with the slot C in the 55 front, and the upper portion of b, down to

the line E, below the slot, is attached to A by glue, paste, or otherwise, so that a coin inserted in C will pass through C¹ and drop into the receptacle B. The back of the receptacle B may have instructions, records, 60 addresses or any other desired matter printed or written on it.

In the form shown in Figures 1 and 2 the front A and the back B are both rectangular and of the same width. The upper flap F of the receptacle is narrow enough to be 65 above the slot, and is closed before, or when, the receptacle B is attached to the front A.

In the modified form shown in Figures 3, 4 and 5, the front A¹ has curved sides and 70 the back B¹ is narrower than the front. The flap F' is turned back over the part b''' before, or when, the part b'' is attached to the front A'. When the receptacle B' is detached from the front A', the flap F', as 75 shown in Figure 5, is turned over the slot C' in part b'' and can be fastened so as to close the slot, being wide enough for that purpose.

This gives additional security against 80 coins dropping out of the receptacle when it is carried about after being detached from the front, although in the form shown in Figures 1 and 2, the slot is so near the top of the envelope receptacle, that there is little danger of this happening.

In the form shown in Figures 3, 4 and 5, the parts b'' and b''' of the receptacle B' may be permanently fastened together at the top, or, if not, any opening at the top due to the turning back of the flap F' can be 85 closed when the receptacle B' is attached to the front A', by pasting, glueing or otherwise attaching the top edge of part b''' to the front A' or to the part b''.

This coin receptacle and stand is excellently adapted for banks and savings institutions, and being decorative and attractive in appearance, it is suitable for a desk or table or mantle ornament, and it acts as a constant reminder to save. The back of the receptacle may have any desired directions, addresses or other matter printed or written on it. One convenient feature for the front of my stand is a monthly calendar, and at the end of the month the receptacle can be 100 detached and taken to the bank, and a new stand and receptacle supplied.

Various modifications can be made in the size, shape, materials and construction of my collapsible coin receptacle and stand,

and I do not confine myself to the particular embodiment of my invention herein shown and described; but what I claim and desire to secure by Letters Patent is:—

- 5 1. A coin receptacle and stand comprising a stiff front, a back consisting of an envelope detachably secured to said front, slots in said front and said envelope registering with each other, and a flap on said envelope which is bent back when said envelope is attached to said front, and can be fastened over the slot in said envelope when the latter is detached from said front.
- 10 2. A coin receptacle and stand comprising a front of cardboard or like material having a coin slot in its upper part, a back consisting of an envelope with its upper part attached to said front, and having a coin slot which registers with the slot in said front, said envelope being detachable from said front, and having a flap which

can be fastened over the slot in said envelope when said envelope is detached.

- 15 3. A coin receptacle and stand comprising a front of cardboard or similar material, a back having a closed pocket, said front and said back being detachably fastened together at their upper ends and separated at their lower ends so as to form a stable base, a slot in the upper part of said front and a corresponding slot in the upper part of said back, and a flap on said back for fastening over the slot in said back when the latter is detached from the front.

In testimony whereof, I have signed my name to this application, in the presence of two subscribing witnesses, this 14 day of Sept., 1921.

ARTHUR S. McNALLY.
